Primary Examiner — Ian Simmons*Assistant Examiner* — Harold Blackwell, II(74) *Attorney, Agent, or Firm* — Porter, Wright, Morris & Arthur LLP; Ryan L. Willis(57) **CLAIM**

I claim the ornamental design for a swivel bracket, as shown and described.

DESCRIPTION

FIG. 1 is an elevated perspective view from the right front of a swivel bracket, showing my new design, attached to an exemplary basket;

FIG. 2 is a frontal view thereof;

FIG. 3 is a left profile view thereof; and,

FIG. 4 is a top view thereof.

The broken line showing of the basket and bracket is for the purpose of illustrating environmental structure which forms no part of the claimed design.
